UNITED STATES PATENT OFFICE.

RUSSELL R. WATERMAN, OF SAN DIEGO, CALIFORNIA, ASSIGNOR TO SAN DIEGO AERIAL NAVIGATION CO., OF SAN DIEGO, CALIFORNIA, A CORPORATION OF CALIFORNIA.

ATTACHMENT FOR DIRIGIBLE BALLOONS OR GAS-BAGS.

1,103,388.

Specification of Letters Patent. Patented July 14, 1914.

Application filed January 29, 1913, Serial No. 744,865. Renewed May 28, 1914. Serial No. 841,687.

To all whom it may concern:

Be it known that I, RUSSELL R. WATERMAN, a citizen of the United States, and a resident of San Diego, in the county of San Diego and State of California, have invented certain new and useful Improvements in Attachments for Dirigible Balloons or Gas-Bags, of which the following is a specification.

- 10 My invention relates to an attachment adapted to keep the gas pressure uniform when the gas expands and contracts in dirigible balloons or gas bags and to keep the gas evenly distributed therein by means of netting in connection with a windlass, and the principal objects of my invention are, first, to provide an attachment that will make aerial navigation safer, second, to provide an attachment that will facilitate 15 the controlling of said dirigible balloon or gas bag, third, to provide an attachment that can be attached to any dirigible balloon or gas bag, fourth, to provide such an attachment that is simple of construction, 20 durable, automatically operated and easily attached, fifth, to provide an attachment that is positive in its action, and sixth, to increase the netting support of the bag.

With these and other objects in view as will hereinafter appear, my invention consists of certain novel features of construction, combination and arrangement of parts as will be hereinafter described in detail and particularly set forth in the appended 35 claims, reference being had to the accompanying drawings and to the characters of reference thereon, which form a part of this specification, in which:—

Figure 1 is a transverse sectional view of 40 my attachment complete shown in connection with a dirigible balloon, and Fig. 2 is a side elevational view thereof on a smaller scale.

Similar characters of reference refer to 45 similar parts throughout the several views.

In the drawings, numeral 1 represents the gas bag, 2 the ordinary netting, 3 the attachment netting, 4 the auxiliary take up cables, 5 the main take up cables, 6 the pulleys, 7 auxiliary idler pulleys, 8 the main idler pulleys, 9 the windlass and 10 the car.

The gas bag 1 is an ordinary gas bag or dirigible balloon which is covered with an ordinary meshed netting 2. To this netting

2, on each side of the bag is attached a plurality of pulleys 6, which are located as shown best in Figs. 1 and 2, and are rigidly secured to said meshed netting by means of crow-footing. Suspended a short distance below the gas bag the pendant 10 is secured 55 by means of the extended ends of the netting 2. The attachment meshed netting 3 is similar to netting 2, but covers only the portion of the bag at the bottom not covered by the ordinary netting and it is held in 60 place by a plurality of auxiliary take up cables 4 which are rigidly fastened on each side of the netting 3 at its top edge and are each provided with the stops 5^a which will prevent the bag from expanding, thus causing 65 the strain to be on the netting 3 and not on the bag. Said auxiliary cables are passed up and around the pulleys 6, then down and under the idlers 7 and rigidly fastened to the main take up cables 5 as shown 70 best in Fig. 2. These main take up cables 5 are secured at each of the four corners of the meshed netting 3, then pass up and around the pulleys 6, then down and under the idler pulley 8^a, around the idler pulleys 8^b over the main pulleys 8 and down to the 75 drum of the windlass 9 on which they are secured. This windlass 9 consists of a drum 9^a which is provided on one end with a small drum 9^b and is pivotally mounted on 80 the brackets 9^c which are secured at their lower ends to the bottom of the pendant 10. A cable 9^d is rigidly fastened to the small drum 9^b and is wound around a number of 85 times, then secured to the tension spring 9^e 90 which is rigidly secured to the floor of said pendant 10.

Though I have shown and described a particular construction and arrangement I do not wish to be limited to this particular 95 construction and arrangement, but desire to include in the purview of my invention the principles, construction and arrangement substantially as set forth in the appended claims.

It is obvious that with this construction there is provided an attachment that will prevent a gas bag from becoming flabby, sometimes caused by the evaporation or escape of gas therefrom, by means of the 105 extra attachment netting which will automatically draw the lower surface of the bag together by means of the windlass 9, thus

keeping the gas in said dirigible balloon or gas bag evenly compressed and preventing it from moving from one portion of said gas bag or dirigible balloon to another, and, as a result, that it will make aerial navigation safer; that it will facilitate the controlling of said dirigible balloons or gas bags; that said attachment can be readily attached to any dirigible balloon or gas bag; that it is durable and automatic in its action.

Having thus described my invention, what I claim as new and desire to secure by Letters Patent is:—

1. In an attachment for gas bags of the class described, the combination of a netting adapted to fit over the lower surface of said gas bag, a plurality of pulleys mounted on the side of said gas bag, cables attached to the sides of said netting mounted over said pulleys and the ends extending downwardly, a drum on which the ends of said cables are wound, and spring means in connection with said drum for keeping said cables in a certain tension.
2. In an attachment for dirigible balloons, the combination of a netting stretched over the lower surface of said dirigible balloon, a plurality of pulleys mounted along the opposite sides of said balloon, a plurality of cables attached to the sides of said netting extending over said pulleys provided with stops whereby said cables are prevented from traveling too far on said pulleys in either direction, a drum mounted in the car upon which said cables are wound, another cable wound on said drum, and a spring attached to said latter mentioned cable for

holding said net at a certain tension against the lower surface of said dirigible balloon.

3. In an attachment for dirigible balloons, the combination of a netting adapted for the lower surface of a dirigible balloon, a plurality of cables attached to each side thereof, a plurality of pulleys mounted on opposite sides of said balloon some distance from the edges of said netting, a plurality of cables attached to the sides of said netting passing over said pulleys and a spring regulated drum upon which the other ends of said cables are wound.

4. A device of the class described comprising a netting adapted to fit over the lower surface of a gas bag, a plurality of pulleys attached to the netting on each side of said gas bag, a plurality of cables attached to the sides of said netting and passing over said pulleys provided with stops in said cables for preventing said cables from passing through said pulleys after they have reached a certain position, a plurality of idler pulleys for said cables and adapted for guiding them to the positions desired, a drum mounted in the car of the dirigible balloon upon which the ends of said cables are wound, and a spring means in connection with said drum for holding said cables in a certain tension at all times.

In witness whereof, I have hereunto subscribed my name in the presence of two subscribing witnesses.

RUSSELL R. WATERMAN.
